UNITED STATES PATENT OFFICE.

FRANCIS B. CONVERSE, JR., OF NEW HAVEN, CONNECTICUT, ASSIGNOR TO MERGENTHALER LINOTYPE COMPANY, A CORPORATION OF NEW YORK.

LINOTYPE-MACHINE.

No. 880,779.

Specification of Letters Patent.

Patented March 3, 1908.

Application filed May 16, 1907. Serial No. 373,919.

To all whom it may concern:

Be it known that I, FRANCIS B. CONVERSE, Jr., of the city of New Haven, county of New Haven, and State of Connecticut, have invented a new and useful Improvement in Linotype-Machines, of which the following is a specification.

This invention has reference to linotype and similar machines wherein matrices or dies, stored in channels in a magazine, are, during the composition of the lines, discharged by means of escapements operating to release a matrix each time the corresponding key of a connected keyboard is depressed.

10 On account of the sensible lapse of time required for a matrix, after its release, to pass beyond the retaining pawls of the escapement, and on account of the resistance offered to the movement of the escapement by the weight of a full channel of large matrices, it has heretofore been found desirable to operate the escapements by means of power-actuated mechanism which gives a deliberate and controlled movement to the escapement,

15 20 25 the depression of the keys of the keyboard serving simply to release the connections of the escapements to the power mechanism.

The object of this invention is to provide an escapement which shall be operated directly by the depression of the key, thereby avoiding the complications of the intermediate power-actuated mechanism; and which shall require but a minimum of force in the operation of the key, giving a "touch" which does not sensibly vary, whether the channel is full of matrices or nearly empty; and which shall respond, moreover, to the quick, staccato touch of many operators of this class of machines.

30 35 40 45 50 To this end it consists essentially of an escapement having pawls the engaging faces of which are beveled to meet corresponding bevels on the matrices, in such manner that the weight of the column of matrices shall tend to move the escapement to and fro in the directions necessary to release the successive matrices, in combination with a suitable connection with the key-lever of a keyboard, to control its action, as hereinafter more particularly illustrated and described.

In the drawings I have, for the purpose of illustration, shown my improvement as applied to the matrices of the well known commercial Mergenthaler linotypes, with only 55 such modification of the matrices as is re-

quired by the essence of the invention. It is to be understood, however, that it is applicable to any form of matrix which may be made to present the requisite qualifications.

Referring to the drawings,—Figures 1 and 2 are vertical cross-sections through a magazine and attached escapements, showing the escapement in two positions of its operation. Fig. 3 is a rear elevation of the same parts. Figs. 4 and 5 are, respectively, a cross-section and a rear elevation of an alternative form of the escapement-operating means.

In the drawings, *a* represents the matrix of the familiar form, with ears projecting edge-wise at the upper and lower ends, except that the lower faces of the two ears or lugs on one side of the matrix are beveled, as shown at *a*¹ and *a*². These matrices are stored, one upon another, in channels formed by grooves oppositely cut on the insides of two plates, *b*¹ and *b*², secured together at the proper distance apart and forming jointly the magazine. The magazine is shown as standing in a vertical position, but it may be inclined. Secured to the back of the magazine, near its lower end, is the bar *c*, having slots *c*⁵ cut across its face adjacent to the magazine, one of these slots being in line with each of the magazine channels. Within these slots, pivoted centrally on a rod *c*⁶ which extends the length of the bar, are the one-piece escapements *c*. These escapements consist each of a flat piece of steel of the form shown, having integral therewith the pawls *c*¹ and *c*², the upper faces of which are beveled at *c*³ and *c*⁴ at an angle to correspond to the angle of the matrix ears. Formed in the side of an extension *c*⁸ on the lower end of the escapement is the concentric groove *c*⁹.

Finger-key levers *d*³, pivoted at *d*⁴, are 95 pivotally connected to the lower ends of vertically sliding reeds *d*. These reeds are flat bars guided near their upper ends in slots in the bar *d*², and carry at their upper ends the studs *d*¹ which project into the grooves *c*⁹ 100 of the escapements.

The normal position of the parts is shown in Fig. 1, the reed being in its lowest position and the upper pawl *a*¹ of the escapement projecting through a slot *b*³ in the magazine 105 plate, and supporting the column of matrices by engaging the lowermost matrix by the beveled face of its upper ear. The angle of the engaging faces of the matrix and the escapement pawl is sufficient to cause the 110

weight of the matrices to urge the pawl outward; but the parts are maintained in the position shown by the stud d^1 interlocking with the substantially vertical portion of the 5 groove c^9 . When the finger-key is depressed and the reed raised, the lug traverses this groove, coöperating with the thrust of the matrices to swing the upper pawl of the escapement backward from the magazine, 10 thereby releasing the matrix. The same movement brings the lower pawl into the path of the matrix, immediately below the lower edge of the magazine, stopping the descent of this matrix and those above it, until 15 upon the release of the key, the escapement is again returned to its normal position. The position resulting from the depression of the key is shown in Fig. 2. When the key is released, the weight of the reed, acting 20 through the stud d^1 on the inclined portion of the groove c^9 with which it is at this time in engagement, coöperates with the thrust of the matrix on the lower pawl of the escapement to return the escapement to its normal 25 position, thereby releasing the lower matrix and causing the upper pawl to pass into the path of the upper ear of the succeeding matrix to intercept it in the position shown in Fig. 1. As the escapement returns to this 30 position, the stud d^1 passes back into the vertical portion of the groove c^9 , effectually locking the escapement against movement under the impact of the descending matrices as they are arrested by the upper pawl. The 35 released matrix, on passing out of the magazine, falls into a channel e , formed between plates e^1 mortised into a plate e^2 , and inclosed at the front by a cover-plate e^3 , which conducts the matrix to an assemblage channel of 40 any convenient form, as indicated at e^4 .

Figs. 4 and 5 show a modified form of the connection between the reed and the escapement, the magazine, matrices and escapements being the same as heretofore described, except as below pointed out. In these figures, the escapements are shown with their upper and lower ends beveled at c^{10} and c^{11} in opposite directions at an angle of substantially forty-five degrees. The 45 reeds are guided at their upper ends in slots d^9 formed on the outer face of the bar c^7 , opposite to the slots c^5 carrying the escapements, and are held in place by the fixed cover-plate d^{10} . Projections formed on the 50 reed above and below the bar c^7 , are beveled at d^5 and d^6 at an angle substantially the same as the angle of the adjacent end of the escapement. The faces d^7 and d^8 of these 55 projections act as limiting stops for the downward and upward movement of the reed by engaging the bar c^7 . The vertical face d^{11} of the upper projection of the reed overlaps by a small amount the vertical face 60 of the upper end of the escapement adjacent

to the bevel c^{10} , and holds the escapement 65 normally in the inactive position shown. In this position of the parts, the bevel d^6 stands away from the bevel c^{11} of the escapement a sufficient distance to permit the corner d^{11} to pass off the vertical face of the escapement, when the reed is raised by the depression of the finger-key, before the face d^6 meets the bevel of the lower end of the escapement. Further upward movement of the reed causes a wedging action between 70 the lower angular faces of the reed and the escapement, which coöperates with the thrust of the matrices, to swing the upper pawl of the escapement out of the path of the matrices. During this upward movement of the reed, the bevel c^{10} of the escapement swings under the bevel d^5 of the reed in substantial engagement therewith. The matrix thus released, drops upon the lower pawl of the escapement, whereupon, when 75 the finger-key is released, the wedging action between the upper bevels of the reed and the escapement, as the former descends, coöperates with the thrust of the matrices on the lower pawl, to return the escapement to its 80 original position. The parts are so proportioned that the upper pawl of the escapement enters the magazine upon its return movement, a short distance above the lower ear 85 of the second matrix in the channel, as indicated in Fig. 2, and at the moment the lower matrix is released by the lower pawl, the corner d^{11} of the projection of the reed is approaching the corner at the bottom of the 90 upper bevel of the escapement. Hence it 95 follows that while the matrices in the channel are falling a considerable portion of their length, before being intercepted by the escapement, the reed will descend the necessary small additional distance to bring its 100 corner d^{11} behind the vertical face of the escapement to lock the latter in its inoperative position.

In the escapements herein described, the necessity for springs to cause any part of the 110 action is entirely dispensed with. Beside the depression of the key by the operator, the movements of the parts are occasioned by the action of gravity on the matrices and the reed, coöperating with each other to give 115 movement to the escapement. I have found by experiment that if the escapement pawls and the ears of the matrices are beveled at an angle of about thirty degrees, the outward thrust on the escapement becomes just about 120 sufficient to overcome the frictional resistance between the matrix ear and the escapement. Hence it follows that force only a little more than sufficient to raise the weight 125 of the reed need be applied to the key, and this amount of force is practically unaffected by the weight of the matrices on the escapement. Moreover, the reverse movement of

the escapement being occasioned entirely by the action of gravity, the matrices are given time to pass beyond the escapement pawls, however quickly the key is released after its depression, gravity acting to accelerate both the matrices and the return movement of the escapement at the same relative rates—a condition which does not exist when springs are used to return the parts to their normal 10 positions.

The essence of my invention resides in so forming and arranging the rocking escapement that its to and fro movements will be caused or assisted by the passing matrices; 15 the escapement or the matrices, or both, being provided to this end with inclined or beveled surfaces.

While I prefer to provide the beveled surfaces on both the matrices and the escapements, it will of course be understood that the device will be operative when the beveled surfaces are confined to either of said parts, provided they are given the proper inclination. 20

25 It will be manifest to the skilled mechanic that the form and arrangement of the parts may be widely modified without changing the principle of action or passing beyond the limits of my invention.

30 I believe the present to be the first mechanism adapted to control a passing line of matrices and release them one at a time, in which, by means of beveled surfaces, the weight and impact of the passing matrices 35 are utilized to effect the to and fro movements of the escapement; and the first mechanism in which a moving matrix acts positively to move an escapement to such position that it will engage the next matrix.

40 Having described my invention, I claim and desire to secure by Letters Patent,—

1. The combination of matrices having beveled surfaces and a centrally pivoted escapement having beveled surfaces to coöperate therewith, substantially as described 45 and shown; whereby the passing matrices are caused to urge the escapement to and fro.

2. The combination of a channeled magazine, matrices guided thereby, a centrally pivoted escapement, having beveled surfaces at opposite ends to coöperate with the passing matrices, and means for controlling the vibration of the escapement; whereby the 50 matrices are caused to urge the escapements to and fro, and the escapements controlled

to prevent the improper release of the matrices.

3. In combination with means for guiding the same, gravitating matrices having beveled surfaces, and a centrally pivoted escapement having its ends arranged to contact with said surfaces; whereby the matrices are caused to urge the escapement to and fro. 60

4. In combination with a centrally pivoted escapement and finger-key connections 65 for operating the same, matrices having beveled surfaces to act upon and assist in moving the escapement; whereby the passing matrices are caused to assist in moving the escapement, thereby reducing the labor required to actuate the key. 70

5. In combination with a centrally pivoted escapement having beveled surfaces at its ends, an actuating device adapted to lock the escapement in its normal position; 75 whereby it is prevented from moving accidentally under the weight of the matrices.

6. In combination with means for guiding the same, a series of gravitating matrices and a vibratory escapement to control their 80 descent, the contacting surfaces of the matrices and escapements being inclined in relation to the path of the matrices, and a movable escapement-controlling device, the contacting surfaces between said device and the 85 escapements being inclined, substantially as described.

7. In combination with a vibratory escapement having an inclined groove c^o , a reciprocating reed d having a stud to enter 90 said groove.

8. In combination with a pivoted vibratory escapement, the reciprocating reed d , and a slot and pin connection between said parts; whereby the reed is enabled to positively control the movement of the escapement in both directions. 95

9. In combination with a reciprocating reed d ; a vibratory escapement c containing a groove c^o vertical at the lower end and 100 locking the escapement in position, and curved laterally at the upper end, substantially as shown.

In testimony whereof I hereunto set my hand this seventh day of May, 1907, in the 105 presence of two attesting witnesses.

FRANCIS B. CONVERSE, JR.
